H. JACKMAN.

BROODER.

FILED APR. 26, 1922.

FIG. 1. 18^b

正中三

Fig. 2.

Inventor.

Harry Jackman

Dr. Watson E. Coleman
Attorney

UNITED STATES PATENT OFFICE.

HARRY JACKMAN, OF FORMAN, NORTH DAKOTA.

BROODER.

Application filed April 26, 1922. Serial No. 556,666.

To all whom it may concern:

Be it known that I, HARRY JACKMAN, a citizen of the United States, residing at Forman, in the county of Sargent and State 5 of North Dakota, have invented certain new and useful Improvements in Brooders, of which the following is a specification, reference being had to the accompanying drawings.

10 This invention relates to improvements in brooders, and an important object of the invention is to provide a device of this character which is extremely simple in construction and operation and which may be very 15 readily cleaned.

A further object of the invention is to provide a brooder of the outdoor type having means for protecting the lamp, by means 20 of which the brooder is heated, from gusts of wind and the like, supplying to the lamp at all times a steady current of fresh air to insure proper operation thereof.

These and other objects I accomplish by the construction and arrangement shown in 25 the accompanying drawings wherein for the purpose of illustration is shown a preferred embodiment of my invention and wherein like reference characters designate like parts throughout.

30 In the drawings:

Figure 1 is a perspective view showing a brooder constructed in accordance with my invention;

Figure 2 is a transverse vertical sectional view taken therethrough; and

Figure 3 is a section on the line 3—3 of Figure 2.

Referring now more particularly to the drawings, the numeral 10 indicates a rectangular framework having an open top and bottom. This framework is provided on the inner faces of the under sides thereof with notched brackets 11 adapted for the reception of the lower end of a plate 12. Between the brackets and one end of the frame 10 the upper surface of the frame is covered by a plate 13 which is removable and provided upon the lower surface thereof with batons 14 preventing movement of the plate 13 with relation to the frame, the ends of the batons abutting against the brackets and against the end walls 10^b of the frame 10 and the outer side faces thereof abutting against the side walls 10^a. This plate is provided with perforations 15 for a purpose presently to appear.

The numeral 16 indicates a brooder proper comprising walls 17, a top 18 and a bottom 19. The walls 17 are provided adjacent their upper ends with fresh air inlet openings 20 for the purpose of admitting fresh air to the closed chamber, and one of these walls has formed therein a door 21 closed by a slide 22. The side wall has secured thereto opposite the opening so as to cover 60 the opening when the slide is removed, strips of woolen cloth or the like, as indicated at 23, to prevent the entrance of draft and the loss of heat through the doorway.

The top 18 is preferably formed in hingedly connected sections 18^a and 18^b, the section 18^a being permanently secured to the walls 17. The bottom 19 is provided centrally with an aperture 24 of desired size which is covered, and to the under surface 75 of the bottom 19 is applied a plate 25 extending considerably beyond the edges of the opening and secured to the bottom. The recess thus formed in the bottom is filled with clean fine sand or soft dirt as desired. 80

Secured to the outer surface of the side walls 17 is a depending skirt 26 forming a support for supporting the brooder in spaced relation to the ground. One side of the skirt 26 consists of separate sections having 85 their adjacent ends spaced a distance equal to the width of the plate 12 which normally closes the opening thus formed.

In the use of my device a trench or pit is dug in the ground in which the frame 10 is 90 disposed and the lamp seated upon the ground within the frame at the end thereof remote from that covered by the grating 13. The brooder is then placed over this end so that the plate 12 closes the opening between the skirt sections and when in this position the lamp 28 is disposed beneath the plate 25 to impart its heat thereto for transmission to the dirt or sand disposed in the opening 24. The air to supply the lamp 100 passes through the openings 15 of the plate 13 and between the walls of the frame to the lamp and the gases from the lamp after circulating against the lower surface of the bottom 19 of the brooder pass outwardly at 105 these openings, the lamp heating the earth within the chamber and at the same time preventing crowding of the chicks about the heated dirt or sand. Attention is directed to the fact that the lamp is so disposed as 110 not to be subject to sudden drafts or puffs of wind and is at the same time provided with

an ample amount of air for proper operation. It will furthermore be obvious that the grating 13 will prevent the entrance of rodents beneath the brooder and will also 5 serve to prevent small chicks from falling into the pit in which the frame 10 rests.

From the foregoing it is believed to be 10 obvious that a brooder constructed in accordance with my invention is particularly well adapted for the purpose for which it is intended for the reason that the construction thereof is extremely simple and permits of the use of papers upon the bottom of the brooder to prevent dirtying thereof by the chicks and for the reason that the 15 lamp is materially protected against gusts of wind. It will furthermore be obvious that the construction as hereinbefore set forth is capable of some change and modification without materially departing from the spirit of my invention and I accordingly do not limit myself thereto except as hereinafter claimed.

I claim:

25 1. In a brooder, a frame adapted for arrangement within a pit and having one end thereof covered by a grating, a plate extending upwardly from the frame at one end of the grating, a lamp disposed within the 30 frame and resting upon the bottom of the pit in which the frame is disposed, and a brooder chamber provided with a depending skirt having an aperture therein permitting removal of said lamp, said aperture being 35 normally closed by said plate.

2. In a brooder, a frame adapted for ar-

rangement within a pit and having one end thereof covered by a grating, a plate extending upwardly from the frame at one end of the grating, a lamp disposed within the 40 frame and resting upon the bottom of the pit in which the frame is disposed, a brooder chamber provided with a depending skirt having an aperture therein permitting removal of said lamp, said aperture being normally closed by said plate, an aperture 45 formed in the bottom of the brooder chamber above the lamp, a plate of greater size than said opening secured to the underside of the bottom of the brooder chamber and covering said opening, and a filling of 50 earthy material disposed within the opening.

3. In a brooder, a framework adapted to be disposed within a pit, brackets secured to the adjacent faces of the sides of said framework, a plate having its lower end mounted in said brackets and extending upwardly from the framework, a grating covering the end of the framework at one side of the plate, a brooder chamber having a depending skirt provided with an aperture arranged above the opposite end of the framework, a lamp disposed within the framework at the last named end thereof, said skirt having an aperture therein affording 65 access to said lamp and normally closed by said plate, said plate being removable from said brackets; and said grating being removable from said frame.

In testimony whereof I hereunto affix my 70 signature:

HARRY JACKMAN,
